PUMP

Charles Elliott, Carthage, Mo.

Application August 20, 1945, Serial No. 611,556

3 Claims. (Cl. 103—241)

1

This invention relates to pumps designed primarily for lifting fluids from wells, one of the objects being to utilize air under pressure as the forcing medium while the liquid in the well serves as a means for controlling certain electric circuits, whereby the proper actuation of the pump is effected.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawing, the complete apparatus has been shown in a single figure partly in section and partly in diagram, a portion being broken away.

Referring to the drawing by characters of reference, W designates a well which can be provided with the usual casing 1 and cap 2. Extending through the cap and downwardly within the well to a desired depth is an outflow pipe 3, which is normally closed by check valve 4 adapted to permit the inflow of liquid, but to prevent return flow thereof. This check valve can be removed from the pump through the outflow pipe for repair, if necessary. In the structure illustrated, the outflow pipe is provided, at a point outside of the well, with an air chamber 5 and with a pressure-controlled switch 6 receiving pressure from the pipe. Switches of this type are so well known that it has not been deemed necessary to show or describe the same in detail. It is merely necessary to state that when the pressure in the pipe rises to a predetermined point, the switch will open but at other times the switch will be closed.

The lower portion of the outflow pipe 3 is housed within a cylinder 7, the lower end of which is closed by a lift valve 8 adapted to close under downward pressure but to open under upward pressure. This lift valve or foot valve is protected by a screen 9 secured to the lower end of the cylinder and extending under the valve.

Opening into the upper end of the cylinder 7 is an air input pipe 10, while an air outlet pipe 11 also opens into the upper portion of the cylinder. Both of these pipes 10 and 11 extend through the cap 2 and tube 11 has an electrode 12 supported therein and insulated therefrom. The free end of this electrode is suspended in the cylinder 7 close to the top thereof while the

2

other or upper end of the electrode is mounted in a sealed cap 13 secured in the upper end of pipe 11. An outflow arm 14 extends from the upper portion of the pipe 11 and is controlled by an exhaust valve 15 adapted to be operated electrically.

Another electrode 16 is supported within the pipe 10 and is extended downwardly within cylinder 7 to a point adjacent to the bottom thereof. 10 This electrode, like the electrode 12, is covered with insulation except at the lower or tip end. The upper end of electrode 16 is secured within a sealing cap 17 in the upper end of pipe 10 and adjacent to this upper end said pipe is formed 15 with an extension 18 leading to an air compressor 19 which has been indicated in diagram in the drawing and can be of any desired construction. An electrically operated intake valve 20 is mounted in the extension 18 and can be of any suitable construction. Said extension is also provided with a pressure regulator 21 of any preferred construction.

The electrical circuit forming a part of the pump has been shown in diagram in the drawing. 25 It includes a lever 22 of insulating material which is held normally in one position by spring 23. In the drawing this lever has been shown in an intermediate position which it would occupy only momentarily. The lever 30 carries the armature 24 of an electromagnet 25. The lever also carries separate contacts 26 and 27 each extending toward fixed contacts arranged in pairs, the contacts of one pair being indicated at 28 and 29 and the contacts of the 35 other pair being indicated at 30 and 31. Another movable contact 32 is supported at the opposite side of the lever 22 and is adapted, under certain conditions, to engage spaced contacts 33 and 34.

40 One of the main leads of the circuit has been indicated at 35 and is electrically connected through one side of a transformer 36 to one terminal of valve 15, to contact 31, and to one of the terminals of the switch 6. Lead 35 is also 45 electrically connected to contact 33.

The other side of the transformer 36 has a grounded terminal and is also electrically connected to one terminal of the electromagnet 25. The other terminal of the electromagnet is electrically connected to the contact 28 and to the electrode 12.

50 Contact 34 is electrically connected to the second terminal of exhaust valve 15. Contact 29 is electrically connected to electrode 16 and contact 30 is electrically connected to one terminal

of the valve 20. The second terminal of the pressure control switch is electrically connected to the other main lead of the circuit, indicated at 37.

It is to be understood that cylinder 7 is to be submerged in the liquid in the well where it will fill through the valve 8 which will open under pressure from below. The liquid in the cylinder serves to close a circuit between the cylinder or ground and the electrode 12, and this circuit is maintained by electrode 16 and the cylinder or ground after the liquid leaves the electrode 12, and until the liquid leaves electrode 16. By thus closing the circuit, the air intake valve 20 is actuated so that air from the compressor thus is admitted through the pipe 10 and operates to expell liquid through the outflow pipe 3. When the circuit is broken by the descent of water or other fluid within the cylinder, said circuit is maintained due to the contact of the fluid with the cylinder 7 which, of course, is grounded through the pipe connections and therefore the electromagnet remains energized to keep the movable contacts in initial positions until such time as the level of the fluid drops below the electrode 16. At that time the electrical connection between said electrode and the ground is broken with the result that the electromagnet is de-energized and the spring 23 acts to thrust lever 22 away from the electromagnet so that the circuit is closed between the contacts 33 and 34. This results in breaking the circuit to the valve 20 so that air under pressure is shut off and at the same time the circuit to the valve 15 is closed so that said valve is opened and air can escape from the cylinder. Thus fluid can again rise by its own weight within the cylinders 7 until electrode 12 is contacted thereby, whereupon the foregoing operation will be repeated.

It will be obvious that when the pressure in the pipe 3 reaches the predetermined point, the switch 6 will act to break the circuit and will remain at this pressure until water is drawn off from the outflow pipe. The switch 6 is used to break the circuit when the pump is not in use.

The various electrically operated valves can be of standard construction and for that reason it has not been deemed necessary to illustrate or describe them in detail.

It is to be understood that an air vent 38 can be extended from the cap 2 so as to allow the fluid to rise freely within the well so as to maintain the cylinder 7 submerged.

Although it has been preferred heretofore to place both electrodes in the two air tubes, it is to be understood that, if desired, both electrodes could be put in one tube only although their relative lengths will be the same.

What is claimed is:

1. In a pump a cylinder to be suspended in fluid to be displaced, said cylinder having a valved intake at its lower end, an air inlet pipe and an air outflow pipe opening into the other end of the cylinder, a fluid overflow pipe leading from the cylinder and having a valved inlet adjacent to the inlet of the cylinder, an electrode having an exposed end in the lower portion of the cylinder, the fluid in the cylinder at and above the exposed end of the electrode constituting means for grounding said electrode to the cylinder, a second electrode having an exposed end in the upper end of the cylinder for contact by the fluid when the cylinder is full, an electromagnet in circuit with the electrodes, means controlled by the electromagnet when energized for maintaining a grounded circuit through said magnet by

way of the grounded cylinder, the first named electrode and the fluid therebetween, an electrically opened air exhaust valve in a circuit controlled by said means, air forcing means, a connection therefrom to the air inflow pipe, an electrically closed valve in said connection, said electromagnet being de-energized by the fall of fluid from contact with both electrodes, and means released by the magnet when de-energized for opening the exhaust valve and closing the valve in said connection.

2. In a pump a cylinder to be suspended in fluid to be displaced, said cylinder having a valved intake at its lower end, an air inlet pipe and an air outflow pipe opening into the other end of the cylinder, a fluid outflow pipe leading from the cylinder and having a valved inlet adjacent to the inlet of the cylinder, an electrode having an exposed end in the lower portion of the cylinder, the fluid in the cylinder at and above the exposed end of the electrode constituting means for grounding said electrode to the cylinder, a second electrode having an exposed end in the upper end of the cylinder for contact by the fluid when the cylinder is full, an electromagnet in circuit with the electrodes, means controlled by the electromagnet when energized for maintaining a grounded circuit through said magnet by way of the grounded cylinder, the first named electrode and the fluid therebetween, an electrically opened air exhaust valve in a circuit controlled by said means, air forcing means, a connection therefrom to the air inflow pipe, an electrically closed valve in said connection, said electromagnet being de-energized by the fall of fluid from contact with both electrodes, and means released by the magnet when de-energized for opening the exhaust valve and closing the valve in said connection, an electrode having an exposed end in the lower portion of the cylinder, the fluid in the cylinder at and above the exposed end of the electrode constituting means for grounding said electrode to the cylinder, a second electrode having an exposed end in the upper end of the cylinder for contact by the fluid when the cylinder is full, an electromagnet in circuit with the electrodes, means controlled by the electromagnet when energized for maintaining a grounded circuit through said magnet by way of the grounded cylinder, the first named electrode and the fluid therebetween, an electrically opened air exhaust valve in a circuit controlled by said means, air forcing means, a connection therefrom to the air inflow pipe, an electrically closed valve in said connection, said electromagnet being de-energized by the fall of fluid from contact with both electrodes, and means released by the magnet when de-energized for opening the exhaust valve and closing the valve in said connection,

3. In a pump a cylinder to be suspended in fluid to be displaced, said cylinder having a valved intake at its lower end, an air inlet pipe and an air outflow pipe opening into the other end of the cylinder, a fluid outflow pipe leading from the cylinder and having a valved inlet adjacent to the inlet of the cylinder, an electrode having an exposed end in the lower portion of the cylinder, the fluid in the cylinder at and above the exposed end of the electrode constituting means for grounding said electrode to the cylinder, a second electrode having an exposed end in the upper end of the cylinder for contact by the fluid when the cylinder is full, an electromagnet in circuit with the electrodes, means controlled by the electromagnet when energized for maintaining a grounded circuit through said magnet by way of the grounded cylinder, the first named electrode and the fluid therebetween, an electrically opened air exhaust valve in a circuit controlled by said means, air forcing means, a connection therefrom to the air inflow pipe, an electrically closed valve in said connection, said electromagnet being de-energized by the fall of fluid from contact with both electrodes, and means released by the magnet when de-energized for opening the exhaust valve and closing the valve in said connection, an electrode having an exposed end in the lower portion of the cylinder, the fluid in the cylinder at and above the exposed end of the electrode constituting means for grounding said electrode to the cylinder, a second electrode having an exposed end in the upper end of the cylinder for contact by the fluid when the cylinder is full, an electromagnet in circuit with the electrodes, means controlled by the electromagnet when energized for maintaining a grounded circuit through said magnet by way of the grounded cylinder, the first named electrode and the fluid therebetween, an electrically opened air exhaust valve in a circuit controlled by said means, air forcing means, a connection therefrom to the air inflow pipe, an electrically closed valve in said connection, said electromagnet being de-energized by the fall of fluid from contact with both electrodes, and means released by the magnet when de-energized for opening the exhaust valve and closing the valve in said connection,

CHARLES ELLIOTT.
